Ms. 288

John S. Davy of Troy N.Y.
Letters Patent No. 288. Dated June 4, 1850.

The Schedule referred to in these Letters Patent and making part of the same.

To all to whom these presents shall come:

Be it known that I, John S. Davy, of Troy, in the County of Rensselaer, and State of New York, have invented or produced a new and original design of Stove, which I call the fancy coal burner, and I do hereby declare that the following is a full and exact description of the same, reference being had to the annexed drawings, making a part of this specification, in which Fig. 1. is a vertical front elevation of the whole stove, and Fig. 2. a view of the bottom plate detached from the stove.

My design consists of arabesque ornaments; the stove is square, each side and the back being the same in form and figure as the front, represented, excepting the sides are made whole instead of a door as at a, the back having a pipe hole situated in the panel a.

On the bottom plate I have represented a part of the ornament, that not represented being the same as that represented.

Having thus described and represented my new design, what I claim as new and desire to secure by Letters Patent, is the ornamental design and configuration of Stove; substantially the same as herein described and represented.

Witnesses.
